UNITED STATES PATENT OFFICE.

HOWARD NADIN MOODY, OF NEW ORLEANS, LOUISIANA.

STEAM-TRAP.

1,183,754.

Specification of Letters Patent.

Patented May 16, 1916.

Application filed February 16, 1915. Serial No. 8,508.

To all whom it may concern:

Be it known that I, HOWARD N. MOODY, a citizen of the United States, residing at New Orleans, in the parish of Orleans and 5 State of Louisiana, have invented new and useful Improvements in Steam-Traps, of which the following is a specification.

My invention relates to certain new and useful improvements in steam traps of that 10 type adapted to receive the water of condensation from a steam heating or circulating system and to return such water to the boiler or source of steam supply for reheating.

15 The object of my invention is to provide a simple, reliable, efficient and comparatively inexpensive type of steam trap which dispenses with the use of packed trunnions or other conductive pivotal connections liable to leak or otherwise get out of order.

20 A further object of the invention is to provide a novel construction of balanced receiver together with coöperating valve mechanism for controlling the flow of the water, steam and air, whereby an apparatus which is certain in action and operates in a smooth and even manner is produced.

The invention consists in the features of 25 construction, combination and arrangement of parts hereinafter described and claimed, reference being had to the accompanying drawings, in which:

Figure 1 is a side elevation of a trap constructed in accordance with my invention, 30 showing the receiver in receiving position; Fig. 2 is a rear end elevation of the same; and Figs. 3 and 4 are diagrammatic views illustrating the operation of the device.

40 In carrying my invention into practice, I provide a suitable base, floor or foundation 1, upon which is mounted a frame structure shown in the present instance as consisting of spaced pairs or sets of uprights or brackets 2, 3, and 4. Extending longitudinally between the sides of the frame formed by the opposed brackets or uprights is a tilting vessel or receiver 5, which may be of any suitable size, form and 45 capacity.

50 As shown in the present instance, the receptacle 1 consists of a cylinder provided at or near its rear or receiving end with trunnions 6 journaled in suitable bearings upon the uprights 2 and forming an axis on which the receptacle is mounted to tilt in a ver-

tical plane. At its opposite or forward end the receptacle is suspended by a link 7 from the forward short arm 8 of a weighted balancing beam or lever 9, provided with a depending bracket member 10 pivotally connected, as shown at 11, with the forward brackets or uprights 4, whereby the beam or lever is eccentrically fulcrumed, or pivoted to tilt vertically on an axis located between its center and forward end. The rear or long arm 12 of the lever 9 carries a weight 13 supported by a hanger 14 slidably engaging the arm 12 of the beam whereby it may be adjusted along the beam to vary its 70 leverage, a set screw 15 being provided for securing the weight in adjusted position. When the receiver is in normal position it is held by the balancing leverage of the weight 13 at an angle to the horizontal, the said 75 receiver being tilted or inclined at an upward and forward angle, as shown in Figs. 1, 2 and 3.

The water of condensation flows through a conducting pipe 16, which is connected by 80 a coupling 17 with a pipe 18, designed for the return of the water of condensation to the boiler. Connected with the conductor 17 and leading therefrom to the rear end of the receiver 5 is a flexible pipe or tube 19, 85 through which the water of condensation flows from the pipe 16 to the receiver and through which the water of condensation is subsequently expelled and delivered through the pipe 18 to the boiler. 90

Arranged in the pipes 16 and 18 on opposite sides of the pipe 19 are check valves 95 20 and 21 which open in a forward direction or in the direction of flow of the water. When the receiver 5 is in receiving position the valve 21 is subjected to a preponderance of pressure on the boiler side and is hence held closed, while the water of condensation flows through the pipe 16 and past the check valve 20 and through a pipe 19 into the receiver 5, into which it continues to flow until the weight of the water exerts a leverage on the receiver greater than the opposing leverage exerted by the weighted beam or lever 12, whereupon the receiver will be tilted to 100 discharge position, as hereinafter fully described.

105 Communicating with the steam space of the boiler is a pipe 22, and communicating with the atmosphere is a pipe 23. Connected with the proximate ends of these pipes by a coupling 24 is a flexible pipe or 110

hose 25 which leads therefrom into the upper portion of the forward end of the receiver 5. This pipe is designed to permit air to discharge from the receiver when the latter is filling with the water of condensation, and to provide for the supply of steam to the receiver when the latter tilts to its discharge position so that the water will be expelled and supplied to the boiler under the force of the steam.

Arranged in the pipe 22 is a steam admission or controlling valve 27, whereby the flow of steam is let on and cut off. A valve 28 is arranged in the pipe 23 on the opposite side of the pipe 25 from the valve 27 and is designed to be opened when the receiver is filling for the exhaust of air and to be closed when the receiver is discharging to permit of the supply of steam to said receiver. The valve 28 is open in operation when the valve 27 is closed, and vice versa, said valves operating in alternation with each other.

A mechanism is provided for automatically controlling the valves 27 and 28, and comprises a primary or valve operating lever 29 and a secondary or valve controlling lever 30. The lever 29 is fulcrumed at a point between its ends, as shown at 31, to one of the brackets or uprights 3, and its rear arm is coupled by a link 32 to a crank arm 33 fixed to the stem of the valve 27, while the forward arm of the lever 29 is connected with the stem 34 of the valve 28, whereby in the reverse rocking movements of the lever 29 the valves will be alternately opened and closed.

The lever 30 is fulcrumed at its rear end, as at 35, to the standard or upright 3 above the fulcrum 31 of the lever 29, said lever 30 being otherwise unsupported, except as hereinafter described, so as to have a determined lost motion or floating action, the forward or free end of said lever being provided with a series of notches 36 to adjustably receive the hanger 37 of a weight 38, operating to depress said lever by gravity at the proper point in the cycle of operation of the trap. A contact pin 39 projects laterally from the receiver 5 at a point in advance of its transverse center and is adapted to engage under the lever 30 at a point between the fulcrum 35 and the transverse center of said lever, said lever being provided with an approximately central vertical opening or passage 40 through which extends the upper cylindrical threaded end 41 of a connecting rod 42 pivoted at its lower end to the forward end of the lever 29, whereby the two levers are coupled for conjoint action. The threaded end 41 of the rod 42 receives a pair of upper and lower nuts or adjustable contact members or abutments 43 and 44, which may be positioned at different distances apart to sensitively vary the action of the valve mechanism as required, it being under-

stood that the construction described provides an independent or lost motion connection between the lever 30 and connecting rod 42 to an extent limited by the distance between the contact members or abutments 43 and 44.

In the operation of the apparatus, which may be assumed to be in the receiving position shown in Figs. 1 and 3, the valve 20 is opened under the pressure of the water flowing to the receiver 5 and the valve 21 closed under the pressure of the water in the boiler, while the valve 27 is held closed and the valve 28 open by the lifting action of the contact 39 engaging and elevating the lever 30, which in turn engages the abutment 43 and thereby lifts the forward end of the lever 29 to open the valve 28 and depress the rear end of said lever to close the valve 27. The water of condensation may thereupon flow freely to the receiver 5, while the air discharges through the valve 28 and pipe 23. As soon, however, as the weight of the water filling or approximately filling the receiver 5 establishes a leverage equal to the resisting leverage of the beam or lever 9 the receiver begins to tilt downwardly, and in so doing raises the weighted long arm 12 of the lever 9, which continues to rise as the receiver descends and until the receiver reaches an approximately horizontal position and tilts the lever 9 also to an approximately horizontal position substantially parallel therewith.

On the beginning of the downward movement of the receiver the lever 30 descends under the gravity of the weight 38 with the contact 39, without, however, affecting the valve mechanism until the receiver reaches its discharge position, since the lever 30, through its lost motion connection with the rod 42, simply moves downward in guided contact with said rod until it engages the abutment 44. At this time the receiver will have completed its tilting motion to discharge position, and at the same time the lever 30 transfers motion through the rod 42 to the lever 29, thus tilting or rocking the latter to close the valve 28 and open the valve 27. Steam from the boiler then passes to the receiver through the pipe 25 and as soon as it reaches the proper pressure forces the water back through the pipe 19 and then through the pipe 18 to the boiler, to which it is thus returned from the heating or circulating system to be reheated. As the water discharges the weight and leverage of the receiver are gradually decreased and the weighted beam 9 finally begins to act to raise the receiver, the water continuing to discharge without affecting the valve mechanism until its discharge is completed, during which time the lever 30, which is being carried up against the resistance of its weight by the pin 39, passes on its lost motion travel from the abutment 44 to the

abutment 43 and begins to lift the rod 42. At the instant of final discharge of the water and the return of the receiver backward to normal or filling position by the action of the lever 12, the lever 30 quickly rocks the lever 29 in the reverse direction to that previously described, thereby opening the valve 28 and closing the valve 27 to restore normal conditions, and thus resetting the apparatus for the charging or filling of the receiver with the water of condensation and for a repetition of the above described operation whereby the water of condensation, when a certain amount is supplied to the receiver, is discharged therefrom into the boiler to be reheated.

From the foregoing description, taken in connection with the drawing, the construction and mode of operation of my improved steam trap will be readily understood, and it will be seen that the invention provides a trap which embodies all of the contemplated advantages and is adapted to operate with maximum reliability and efficiency.

While the structural organization disclosed is preferred, it will, of course, be understood that modifications within the scope of the invention as set forth in the appended claims may be made without departing from the spirit of the invention or sacrificing any of the advantages thereof.

I claim as my invention:

1. In a steam trap, an eccentrically pivoted water receiver, means for balancing the weight thereof and returning the same after actuation to normal position, a water supply pipe, a water discharge pipe leading to the water space of the boiler, a single flexible combined water inlet and outlet pipe connecting the pivoted end of the receiver with said water supply and discharge pipes, check valves in said water supply and discharge pipes on opposite sides of said combined inlet and outlet pipe, a steam supply pipe, an air exhaust pipe, a flexible combined steam inlet and air outlet pipe connecting said steam supply and air exhaust pipes with the opposite end of the receiver, controlling valves in the steam supply and air exhaust pipes on opposite sides of said flexible inlet pipe, and means actuated by the movements of the receiver for simultaneously and alternately opening and closing said controlling valves.

2. In a steam trap, the combination of a tilting balanced receiver, water supply and discharge conductors communicating with the receiver, steam inlet and air discharge conductors communicating with the receiver and having controlling valves therein, a lever pivotally connected between its ends for rocking motion and connected at its ends with said valves for alternately opening and closing the same, a second lever pivotally mounted at one end, means acting

upon the opposite end of said second lever for depressing the same when free for such motion, a direct operating connection between the intermediate portion of the second named lever and one end of the first named lever for controlling the movements of the latter, and a member carried by the receiver and free from connection with the second named lever but arranged for contact therewith to effect up and down swinging movements of the said second named lever with the receiver.

3. In a steam trap, the combination of a receiver pivotally mounted at one end to swing in a vertical plane, a weighted counter-balancing lever connected with the free end of said receiver, water supply and discharge conductors communicating with the receiver, steam inlet and air discharge conductors communicating with the receiver and having controlling valves therein, a lever pivotally connected between its ends for rocking motion and connected at its ends with said valves for alternately opening and closing the same, a second lever pivotally mounted at one end and counter-weighted at its opposite end, a direct operating connection between the intermediate portion of the second named lever and one end of the first named lever for controlling the movements of the latter, and a member carried by the receiver and free from connection with the second named lever but arranged for contact therewith to effect up and down swinging movements of the said second named lever with the receiver.

4. In a steam trap, the combination of a water receiver pivotally mounted to swing in a vertical plane, means connected with the receiver for balancing the weight of said receiver and returning the same after actuation to normal position, said means operating to normally maintain the receiver in an inclined position, water supply and discharge connections, steam inlet and air discharge connections, controlling valves in said steam inlet and air discharge connections, a lever pivotally mounted intermediate its ends and having its ends connected with said valves for alternately operating the same upon reverse rocking movements of said lever, a second lever pivotally mounted at one end at a point above the pivot point of the first named lever, a weight upon the free end of the second named lever for swinging the same downwardly when free for movement, a direct connection between the intermediate portion of the second named lever and one of the arms of the first named lever, said connection having a loose sliding and pivotal engagement with the second lever and spaced contacts for co-operation therewith, and a contact device upon the swinging receiver operating to engage and lift the second lever on the upward

- movement of said receiver and to permit downward movement of said second lever under the action of its weight upon the downward movement of the receiver.
5. In a steam trap, the combination of a water receiver pivotally mounted to swing in a vertical plane, means connected with said receiver for balancing the weight of said receiver and normally maintaining it 10 in an inclined position and returning it to normal position after actuation, water supply and discharge connections with one end of the receiver, steam supply and air discharge connections with the other end of 15 the receiver, controlling valves in said steam supply and air discharge connections, an intermediately pivoted rocking lever having its respective arms connected with said valves for alternately operating the same on reverse movements of said lever, a second lever pivotally mounted at one end for vertical swinging movement, a weight upon the opposite end of said second lever for imparting downward motion thereto, a link 20 pivotedly connected with one arm of the first named lever and having a loose guided connection for sliding and pivotal movements with the intermediate portion of the second lever, said link being provided with 25 spaced contacts above and below the second lever for coöperation therewith, and a contact member upon the receiver arranged to engage under and lift the second lever upon the upward movement of said receiver and 30 to move downwardly and away from said lever to permit downward movement thereof on the downward movement of the receiver.
6. In a steam trap, the combination of a 40 tilting receiver, gravity controlled means for balancing the same, means for conducting water to and discharging it from the receiver, air discharging and steam supplying means communicating with the receiver and 45 including air and steam controlling valves, a rocking lever connecting said valves for alternately opening and closing the same, a second lever having a lost motion connection with the first named lever, and means controlled by the receiver for operating said 50 second lever.
7. In a steam trap, the combination of a 55 tilting receiver, gravity controlled means for balancing the same, means for admitting water to and discharging it from the receiver, air and steam conducting means communicating with the receiver and including air and steam controlling valves, a rocking lever connected with said valves for alternately opening and closing the same, a second rocking lever, a weight for depressing the same when the receiver tilts downward, a contact device on the receiver for lifting said lever when the receiver tilts upward, 60 and a rod pivotally connected with the first 65 named lever and having a sliding and pivotal lost motion connection with the second named lever.
8. In a steam trap, the combination of a 70 tilting balanced receiver, water supplying and discharging means connected with the receiver, air discharging and steam supplying means communicating with the receiver and including air and steam controlling valves, a pivoted actuating element governing said valves for alternately opening and closing the same, a second pivoted actuating element 75 having a lost motion connection with the first named actuating element, and means controlled by the receiver for operating said second actuating element.
9. In a steam trap, the combination of a 80 tilting water receiver, a pin projecting laterally therefrom, an upright, a weighted lever resting at an intermediate point on said pin and pivotally connected at one end to said upright, a second lever pivotally connected to said upright so as to have a long arm and a short arm arranged parallel to 85 said first lever, a rod pivotally connected to the free end of said short arm and provided with a threaded extension that loosely passes through said first lever adjacent said pin, nuts adjustably mounted on the threaded extension and adapted to alternately engage 90 opposite edges of said first lever, and valves under the control of said second lever for alternately allowing steam to enter and air to escape from said receiver.
10. In a steam trap, the combination of 95 a tilting water receiver, a pin projecting laterally from said receiver, an upright, a weighted lever resting at an intermediate point on said pin and pivotally connected at one end to said upright, a second lever 100 pivotally connected to said upright so as to have a long arm and a short arm arranged parallel to said first lever, a rod pivotally connected to the free end of said short arm and provided with a threaded extension that 105 loosely passes through said first lever adjacent said pin, nuts adjustably mounted on the threaded extension and adapted to alternately engage opposite edges of said first lever, and valves under the control of said second lever for alternately allowing steam to enter and air to escape from said receiver.
11. In a steam trap, the combination of a 110 tilting balanced receiver, water supplying and discharging means connected with the receiver, air and steam conducting means communicating with the receiver and including air and steam controlling valves, a pivoted actuating element governing said valves for alternately opening and closing the same, a second pivoted actuating element, means for depressing the same when the receiver tilts downwardly, a contact device on the receiver for lifting said second actuating element when the receiver tilts 115
- 120
- 125
- 130

upwardly, and a rod pivotally connected with the first named actuating element and having a sliding and pivotal connection with the second named actuating element.

5 12. In a steam trap, the combination of an eccentrically pivoted water receiver, water inlet and discharge connections, air inlet and discharge connections, including controlling valves for alternately admitting air and steam upon reverse movements of the receiver, a valve actuating lever fulcrumed at a point between its center and one of its ends, said lever having its long arm connected with the steam controlling valve and its short arm connected with the air controlling valve, a valve controlling lever pivoted at one end above the pivotal support of the valve actuating lever and having a slot at a point in advance of its transverse cen-

10

15

ter, a link pivotally connected with the short arm of the valve actuating lever and extending upwardly through said slot, abutments upon the link above and below the controlling lever and forming a lost-motion connection between said link and lever, a counterweight upon the outer end of the controlling lever, and a contact device upon the receiver adapted for engagement with said controlling lever at a point between the fulcrum of said lever and said lost-motion connection, at a predetermined time in the movements of said receiver.

In testimony whereof I affix my signature in presence of two witnesses.

HOWARD NADIN MOODY.
